PHOTO-TOUCH SENSITIVE APPARATUS

Ernest V. Bereche, Flushing, N. Y., assignor to
Industrial Electronic Control Co. Inc., New
York, N. Y., a corporation of New York

Application April 4, 1934, Serial No. 719,054

3 Claims. (Cl. 250—41.5)

This invention relates to a photosensitive and a touch sensitive apparatus, and has for one of its objects to provide a novel, a simple and highly efficient apparatus of this character which may 5 be used for the purpose of stopping a printing press should a break occur in the web of paper in the press or should a workman approach dangerously near the plate or impression cylinders or other exposed moving parts of the press.

10 The invention has for its further object to provide an apparatus of the character stated which may be also used for the purpose of controlling an elevator, sounding a burglar alarm, and the like.

15 With the foregoing and other objects in view, the nature of which will appear as the description proceeds, the invention resides in the construction, combination and arrangement of parts hereinafter fully described and claimed, and illustrated in the accompanying drawings, wherein:

Figure 1 is a view partly in front elevation and partly in vertical section of the apparatus;

Figure 2 is a sectional view taken on the horizontal plane indicated by the line 2—2 of Figure 1;

25 Figure 3 is a sectional view taken on the vertical planes indicated by the line 3—3 of Figure 2;

Figure 4 is a sectional view taken on the horizontal plane indicated by the line 4—4 of Figure 1;

Figure 5 is a diagrammatic view of the apparatus, and

Figure 6 is a diagrammatic view of the bridge circuit.

The apparatus comprises a transformer 1 which includes a primary 2 and secondaries 3 and 4. The primary 2 is supplied with alternating current preferably of commercial frequency and voltage, from line wires 5 and 6, to which it is connected by conductors 7 and 8 terminally provided with a plug 9. One of the line wires, such as 6, 30 may be grounded, as indicated at 9a.

An electron-discharge tube 10 has its cathode 11 connected to the secondary 3 by conductors 12 and 13. The anode 14 of the tube 10 is connected by a conductor 15 to a relay 16 which is 35 connected by a conductor 18 to the secondary 4. The control electrode or grid 19 of the tube 10 is connected by conductors 20, 20 and 20b to a potentiometer 21 which has its coil 22 shunted across the cathode supply conductors 12 and 13, 40 and which has one of its ends grounded, as at 23 to the chassis 36. A normally closed meter-jack 24 is connected in the conductor 15 between the anode 14 and the relay 16.

45 A photoelectric cell 25 has its cathode 26 con-

nected to the conductor 20 between the control electrode or grid 19 of the tube 10 and the potentiometer 21. The anode 27 of the cell 25 is connected by a conductor 28 to a variable resistance 29 which is connected to the conductors 13 and 18 across the terminals of the secondary 4. A condenser 30 is connected in the conductor 20 between the potentiometer 21 and the cathode 26 of the cell 25. A touch control wire 31 is connected to the conductor 20 between the control electrode 10 or grid 19 of the tube 10 and the cathode 26 of the cell 25. A touch element 31a, which may be in the form of a solid metal disc, a mesh disc or a metal rod, is connected to the free terminal of the touch control wire 31.

15 Fig. 6 is a diagram of applicant's bridge circuit which may be of help in the following explanation.

The apparatus includes an electrical bridge composed of two legs. One of the bridge legs comprises the conductor 13, that portion of the potentiometer 21 between conductors 13 and 20b, conductor 20b, condenser 30 and conductor 20a.

The other leg of the bridge comprises that portion of the resistance 29 between conductors 13 and 28, conductor 28 and photoelectric cell 25. 25 Negative potential is on one side of the bridge (when plate is positive) and the grid is connected to the other side. Touch controls 31 and 31a is secured to conductor 20 at the junction of the bridge legs which leads to the grid of tube 10.

30 The cathode 11 of the electron-discharge tube 10 is heated by current induced in the secondary 3 of the transformer. The anode 14 of tube 10 is energized every half cycle by a positive potential from secondary 4 of transformer 1 through conductor 18, relay 16 and meter-jack 24. The pulsating positive potential of the cathode circuit is on the ground side of the potentiometer 21 and the negative potential of this circuit is on the 40 other side of the potentiometer. The potentiometer 21 is used in conjunction with variable resistance 29 to adjust the bridge to a balanced condition so that with photoelectric cell 25 darkened and touch control 31 and 31a untouched the grid 45 19 of tube 10 will not have any potential impressed upon it. This will allow the grid to float, causing a small amount of plate current to flow, energizing relay 16. When the photoelectric cell 25 is activated by light or the touch control element 31 and 31a is touched, the balance of the bridge is 50 upset, causing a negative potential to grid 19, de-energizing the relay 16.

55 This apparatus may be used as a paper-break detector for newspaper presses and to protect the

pressmen from injury. To adapt it for use on a press, the apparatus is mounted in a casing 33 which may be supported within the press in rear of the web of paper and at a point forwardly 5 beyond the plate and impression cylinders of the press. The casing 33 is provided in its front wall with openings or eyes 34 and 35, in rear of which the photoelectric cell 25 is mounted. The several parts of the apparatus are secured to a 10 plate or chassis 36 within the casing 33 as shown in Figure 2. The photoelectric cell 25 is secured to the chassis 36 between the eyes 34 and 35 and a shield 37 within the casing 33, the shield serving to protect the cell from all rays of light except those entering the casing through the eyes 15 34 and 35. The potentiometer 21 is grounded to the chassis 36. Electric lamps are arranged in front of the web of paper in alignment with the openings or eyes 34 and 35. When the paper 20 is without a break, the photoelectric cell 25 is in the darkened state and current is flowing through the relay 16. When a break occurs in the web of paper, the lamp rays pass through the break and activate the photoelectric cell 25, with 25 the result that the negative potential of the electrode or grid 19 is sufficiently increased to effect the deenergization of the relay 16. The touch element 31^a of the control wire 31 may be supported in any suitable manner near the plate 30 and impression cylinders or other exposed moving parts of the press. As the control wire 31 and its touch element 31^a are adjusted to the proper grid bias of the potentiometer 21, the body potential of a person touching the element 31^a will 35 increase the negative potential of the control electrode or grid 19 sufficiently to effect the deenergization of the relay 16. Suitable electrical means may be provided for interrupting the power source of the press and/or severing or 40 bursting the web of paper near the roll when a break occurs in the web of paper or when a pressman contacts with the touch element 31^a. Such means may include electric switches 38 and 39, which are adapted to be opened by electro-magnets 45 40 and 41, respectively. The electro-magnets 40 and 41 are under the control of an electric switch 42 which comprises a contact 43 connected by a conductor 44 to the line wire 5, a contact 45 connected by a conductor 46 to the magnet 40 50 and a contact 47 connected by a conductor 48 to the magnet 41. The magnets 40 and 41 are connected by a conductor 49 to the line wire 6. The switch 42 also comprises an electro-magnet 50, the armature 54 of which constitutes a movable 55 contact of the switch 42. The contact 54 is normally urged in a direction to engage the contacts 43, 45 and 47 by a spring, not shown. The magnet 50 is connected by a conductor 51 to the conductor 8, and is connected by a conductor 52 to the fixed contact 17^a of the relay switch 17. The movable contact 17^b of the relay switch 17 is 60 connected by a conductor 53 to the conductor 7. When the photoelectric cell 25 is in the darkened state the relay 16 will be energized and will hold the switch 17 closed. The switch 17 will hold the circuit of the magnet 50 closed and this magnet will hold the movable contact 54 out of engagement with the contacts 43, 45 and 47. When, however, a break occurs in the web of paper 65 or a workman contacts with the touch element 31^a, the relay 16 will be deenergized. The consequent opening of the relay switch 17 will open the circuit of the magnet 50, with the result that the contact 54 of switch 42 will be released for 70 movement into engagement with the contacts 43, 75

45 and 47 to close the circuits of the magnets 40 and 41. The closing of these circuits results in the opening of the switches 38 and 39, and the opening of these switches effects the stopping of the press and/or the severing of the web of paper 5 feeding through the press.

The apparatus may be used to protect workmen from injury by the moving parts of laundry and other machines. When the apparatus is used for this purpose, the eyes 34 and 35 will be closed 10 and the touch element 31^a will be supported in such relation to the exposed moving parts of the machine that should a workman place his hand or fingers dangerously close to such moving parts he will contact the touch element 31^a and thus 15 cause the deenergization of the relay 16 and the operation of means under the control of the switches 17 or 42 for stopping the machine. The apparatus may also be used to control elevators and to protect vaults. When the apparatus 20 is used to protect vaults, the touch element 31^a may be concealed beneath a rug or mat or in any other suitable manner, it only being necessary to so arrange the touch element 31^a that the body 25 potential of the person approaching the vault will be impressed upon the touch element. This element is so sensitive that it can not be insulated from the body potential. When the apparatus is used to protect a vault, the switch 42 will be connected to a bell or other suitable alarm. The 30 apparatus may be used as a light sensitive device or as a touch sensitive device or as a combined light and touch sensitive device for many purposes other than those hereinbefore set forth, and its use may comprehend the controlling of any kind 35 of signal, alarm, machine break or the like.

The conductors 7, 8, 44 and 48 are encased in armored cables 54 and 55, and carried into the casing 33 through a box 56 on the side of the 40 casing.

It will be further understood the invention is adapted for use in connection with general alarm systems, e. g., burglar alarms, and wherein the apparatus will respond or operate quite regardless of whether the intruder is equipped with the usual 45 devices for insulation purposes. That is to say, the apparatus is insulation proof and will operate to sound an alarm just so long as its instruments are in any way interfered with.

What I claim is:

1. In combination with an electron-discharge tube including a cathode, anode and grid and a power transformer including a secondary connected to the cathode and a secondary connected to the anode; a potentiometer having one end grounded and the other end connected to the common terminal of the anode and cathode transformer secondaries, a resistance between the terminals of the anode transformer secondary secured to the common terminal of the anode and cathode secondaries and the other end secured to the anode; a condenser between a portion of the potentiometer and the grid, a photocell between a portion of the resistance and grid, a touch control element connected to said grid whereby there is formed a bridge comprising a portion of the potentiometer and condenser and touch element as one leg of the bridge and a portion of the resistance and photocell as the other leg of the bridge, said bridge constituting a balanced circuit when the photocell is darkened and the touch control element is undisturbed by proximity of a body thereto.
2. In an electrical control system a bridge unit comprising a first resistor in the first leg, a second 70

resistor in the second leg, a photo-electric cell in the third leg, and a condenser in the fourth leg, an electron discharge tube having an anode, cathode, and grid; a connection from the junction of the first and second resistors to the cathode, a connection from the junction of the photoelectric cell and condenser to the grid, and a capacitance actuated control element whose capacity varies with the proximity of any body which approaches it connected to the grid.

5. In combination an electron-discharge tube, including a cathode, anode and grid, a power transformer including a secondary connected to

the cathode and a secondary connected to the anode, a potentiometer connected across the terminals of the cathode and having one terminal of its coil grounded, a resistance connected across the terminals of the secondary connected to the anode, a condenser between the potentiometer and grid, and a photoelectric cell having its cathode connected between the grid and the condenser and having its anode connected to the resistance, and a touch element connected between the grid 10 and the cathode of the photoelectric cell.

ERNEST V. BERECHE.
